UNITED STATES PATENT OFFICE.

FREDERICK W. SCHWENCK, OF CINCINNATI, OHIO.

DESIGN FOR A FLASK.

Application filed December 17, 1923. Serial No. 8,065. Term of patent 7 years.

To all whom it may concern:

Be it known that I, FREDERICK W. SCHWENCK, a citizen of the United States of America, and a resident of Cincinnati, in the county of Hamilton and State of Ohio, have invented a new, original, and ornamental Design for a Flask, of which the following is a specification, reference being made to the accompanying drawing, forming a part thereof.

Fig. 1 is a front elevation of a flask showing my new design.

Fig. 2 is an elevation of a flask showing my new design at right angles to the showing in Fig. 1.

Fig. 3 is a bottom plan view of a flask showing my new design.

Fig. 4 is a top plan view of a flask showing my new design.

I claim:

The ornamental design for a flask, as shown.

FREDERICK W. SCHWENCK.
